DETACHABLE SHOE HEEL

William J. Collins, Emporia, Kans.

Application February 20, 1933, Serial No. 657,697

6 Claims. (Cl. 36—36)

My invention relates to a detachable shoe heel, tip, or sole.

An important object of the invention is to provide means for detachably mounting a heel or sole upon the shoe, in a manner which will permit of the ready separation of the heel or sole member, and will securely hold the same in position, in close contact with the shoe part.

A further object of the invention is to provide attaching means which are entirely covered by the heel or sole member, and are invisible in use.

A further object of the invention is to provide means for securely anchoring an attaching plate to the heel or sole member.

15 A further object of the invention is to provide means for detachably connecting the heel member with the shoe and so constructed that the heel is placed in position by a forward movement with respect to the shoe, and is automatically locked 20 in the operative position.

Other objects and advantages of the invention will be apparent during the course of the following description.

In the accompanying drawing, forming a part 25 of this specification, and in which like numerals are employed to designate like parts throughout the same,

Figure 1 is a side elevation of a heel member embodying my invention, showing the same in place upon the shoe,

Figure 2 is a central vertical longitudinal section through the same.

Figure 3 is a plan view of the heel member removed.

35 Figure 4 is a bottom plan view of the lift of the heel, showing the attaching plate.

Figure 5 is a transverse section taken on line 5—5 of Figure 1.

Figure 6 is a central vertical longitudinal section through the completed heel, showing the mode 40 of separation.

Figure 7 is a transverse section taken on line 7—7 of Figure 1, and,

Figure 8 is a central vertical longitudinal section 45 through a heel embodying a modification of the invention.

In the drawing, wherein for the purpose of illustration is shown a preferred embodiment of my invention, the numeral 10 designates a shoe, of any well known or preferred construction, having a heel 11, embodying a lift 12, formed of leather or the like, and a heel member 13, preferably formed of rubber, or the like.

The means for detachably connecting the heel member 13 and the lift 12 embodies an upper

attaching plate 14, preferably formed of sheet metal, which is resilient. The attaching plate is secured to the lift 12 by screws 15, although other suitable means may be employed, such as nails, cement, or the like. It is preferred that the attaching means be arranged upon the inner portion of the attaching plate, leaving the marginal edge 16, of the attaching plate free, such marginal edge being offset downwardly, as shown. This marginal edge is generally U-shaped with its open end facing forwardly. Since the marginal edge is free, it possesses the desired resiliency, and is capable of bending locally from the lift 12, within limits. The attaching plate 14 is provided at its forward end with a depending 65 flange 15a, having an opening 16a formed therein.

The numeral 17 designates a companion lower attaching plate, which is preferably formed of metal, and is resilient. This lower attaching plate has its marginal edge bent inwardly upon itself for affording a socket 18, which is generally U-shaped, with its open end arranged forwardly. This socket 18 is also U-shaped in cross-section, with its open side disposed inwardly. This socket 70 is adapted to receive the marginal edge 16 of the companion attaching plate. The attaching plate 17 is mounted within a recess 19, formed in the upper face of the heel member 13, whereby the top of the socket 18 is substantially flush with the marginal flange 20, of the heel member 13. 75 Since this flange 20 contacts closely with the lift 12 when the heel member is in place, the attaching means is completely covered from view.

As more clearly shown in Figures 3 and 7, the lower attaching plate 17 has anchor elements or tongues 21, stamped therefrom, at spaced intervals, and at points inwardly of the socket 18. These tongues are bent downwardly and outwardly, affording horizontal extensions 22, as shown. The stamping of the tongues produce openings 23. The rubber heel member 13 is preferably cast or molded about the attaching plate 17, and the anchor elements or tongues 21 are embedded within the material of the heel member, and portions 23' of the rubber also enter and become 80 embedded within the openings 23, thereby affording a strong connection between the rubber heel member and the attaching plate.

The lower attaching plate 17 is provided near its forward end with upwardly bent locking 85 tongues 24, disposed at a right angle thereto and adapted to enter notches 25, formed in the forward end of the upper attaching plate 14.

The upper attaching plate 14 is provided at its 90 central longitudinal axis and near its forward 95 end with upwardly bent locking tongues 26, disposed at a right angle thereto and adapted to enter notches 27, formed in the forward end of the lower attaching plate 17.

end, with a downwardly projecting spherically curved boss or lug 26, stamped therefrom, and this boss is preferably provided with a guide groove 27, extending through the central longitudinal axis of the boss. The lower companion attaching plate is provided with a spherically curved recess 28, to receive the boss 26, and this recess is disposed at the central longitudinal axis of the attaching plate 17. The plate 17 is provided at its forward end with a guide groove 29, which leads to the recess 28, and is disposed in the central longitudinal axis thereof. When the lug 26 enters the recess 28, it serves as additional means to lock the plate 17 with the plate 14, against relative rearward longitudinal movement, and these parts also serve to co-act with an implement, such as a nail 30, for withdrawing the tongues 24 from within the notches 25.

The operation of the device is as follows:

When it is desired to place the heel member 13 in position upon the lift 12, the heel member is brought in proximity to the rear end of the lift 12, and the socket 18 is placed upon the forward end of the marginal edge 16, and the heel member 13 is then moved longitudinally forwardly with relation to the lift, until the marginal flange has been entirely inserted within the socket 18, at which time the locking tongues 24 will enter the notches 25 and the boss 26 will enter the recess 28. The heel member 13 is now securely locked against relative rearward movement with relation to the lift 12. To separate the heel member from the lift, an implement, such as a nail, is passed through the opening 16' in the flange 15', and this nail is guided by the groove 8 and groove 27, so that its forward end passes between the boss 26 and the recess 28, at their central longitudinal axis. The marginal edge 16, and the wall of the socket being resilient, a bending action occurs, as illustrated in Figure 6, and the locking tongues 28 are withdrawn from the notches 24, whereby the heel member 13 may now be shifted rearwardly, and separated from the lift 12. The marginal flange 16 and socket 18 are resilient and are so tensioned that they normally serve to hold the flange 20 of the heel in firm contact with the lift, whereby the attaching means is completely concealed.

In Figure 8, I have shown a modification of the invention, wherein 12' designates the heel of a lady's shoe, and 13' the heel member or tip. Due to the fact that the tip is relatively thin, the attaching plate 14 cannot be embedded within this tip, and the attaching plate 14 and the companion lower attaching plate 17 are, therefore, reversed. The attaching plate 14 is mounted within a recess formed in the lower end of the heel 13', so that the marginal edge or flange 16 is covered from side vision. The attaching plate 14 is secured to the tip 13'. All other parts remain substantially identical with those shown and described in connection with the first form of the invention.

It is to be understood that the forms of my invention herewith shown and described, are to be taken as the preferred examples of the same, and that various changes in the shape, size and arrangement of parts may be resorted to without departing from the spirit of my invention, or the scope of the subjoined claims.

Having fully described my invention, what I claim is:—

1. The combination with the wear member of a shoe having a recess in its upper face, of a lower attaching plate arranged within the re-

cess and secured to the wear member and having its marginal edge bent inwardly to form a generally U-shaped socket which is U-shaped in cross section, an upper attaching plate to be secured to the shoe and having a free marginal edge for insertion within the socket, locking tongues carried by the lower attaching plate and projecting upwardly to engage with the upper attaching plate, and means whereby the lower attaching plate may be bent downwardly with relation to the upper attaching plate for withdrawing the locking tongues from engagement with the upper attaching plate.

2. The combination with the rubber wear member of a shoe having a recess in its upper face, of a lower attaching plate mounted within the recess and having a marginal socket and anchor elements disposed inwardly of the socket and embedded within the rubber member, said attaching plate also having a depression arranged between the anchor elements, an upper attaching plate having a marginal edge to enter the socket, said upper attaching plate also having a tapered boss to enter the depression of the lower attaching plate, means arranged within the marginal edge for attaching the upper plate to the shoe, locking tongues carried by the lower plate and adapted to engage with the upper plate, and means whereby an implement may be passed beneath the boss for separating portions of the attaching plate and thereby shifting the locking tongues out of engagement with the upper plate.

3. The combination with the heel member of a shoe provided at its lower end with a recess, of an upper attaching plate arranged within the recess and secured to the heel member and having its marginal edge bent inwardly to form a generally U-shaped socket which is U-shaped in cross-section, a wear member, a lower attaching plate secured to the wear member and having a free marginal edge for insertion within the socket, locking tongues carried by the upper attaching plate and projecting downwardly to engage with the lower attaching plate, and means whereby the lower attaching plate may be bent downwardly with relation to the upper attaching plate for withdrawing the locking tongues from engagement with the lower attaching plate.

4. A device for detachably connecting a heel and heel member of a shoe, comprising a pair of resilient plates, one plate being attached to the heel and the other to the heel member, one plate having socket means which is generally U-shaped in cross-section and also having a laterally projecting locking tongue, the other plate having a marginal edge for insertion within the socket means, the locking tongue being adapted to engage with the companion plate to normally prevent relative longitudinal movement in one direction between the plates, the arrangement being such that one plate may be bodily flexed laterally to cause the locking tongue to disengage the companion plate.

5. A device for detachably connecting a shoe part and wear member, comprising a pair of resilient plates, one plate being attached to the shoe part and the other plate to the wear member, one resilient plate having marginal socket means which is generally U-shaped in cross-section and also having a relatively short laterally projecting locking tongue arranged adjacent to the free end of such resilient plate and substantially within the length of such resilient plate, the other resilient plate having a marginal edge for insertion within the socket means, the lock-

ing tongue being adapted to engage with the companion plate adjacent to its free end to prevent relative longitudinal movement in one direction between the two plates, the arrangement being such that one plate may be bodily flexed laterally at its free end from the companion plate to cause the locking tongue to disengage the other plate.

6. A device for detachably connecting a shoe part and wear member, comprising a pair of plates, one of said plates being resilient, one plate being attached to the shoe part and the other plate to the wear member, one plate having marginal socket means which is generally

U-shaped in cross-section, a relatively short locking tongue carried by one plate adjacent to its free end and projecting laterally therefrom for engagement with the other plate adjacent to its free end, the other plate having a marginal edge for insertion within the socket means, one plate having a laterally projecting shifting member provided with an inclined face for engagement with an implement to be inserted between the plates for causing the resilient plate to be bodily flexed laterally from the companion plate and the locking tongue caused to disengage the other plate.
